UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

TROLLEY-WIRE CLAMP.

1,355,614.

Specification of Letters Patent.

Patented Oct. 12, 1920.

Application filed December 28, 1918. Serial No. 268,728.

To all whom it may concern:

Be it known that I, SAMUEL S. MATTHES, a citizen of the United States, residing at Mansfield, in the county of Richland and State of Ohio, have invented certain new and useful Improvements in Trolley-Wire Clamps, of which the following is a specification.

This invention relates to improvements in clamps and has particular reference to the type of clamps used for suspending conductors or wires of electric railway systems or the like.

One object of the invention is to provide an improved clamp of this character which will be simple, durable and strong in construction, effective and efficient in operation, and which can be manufactured at a low cost.

Another object is to provide an improved clamp which is free of separable parts, which has positive action, and which can be readily inserted into and removed from operative position.

A further object is to provide an improved clamp of the character referred to, having means for detachably and adjustably securing the clamp to a support or hanger and having jaws whereby a perfect alinement with the wire may be obtained when the parts are secured together.

Another object of the invention is to provide an improved clamp for suspending wires, cables, conductors, or the like which comprises clamping ends for engaging the wires and a toggle operable to move and maintain said ends in clamping position.

To the attainment of these ends and the accomplishment of other new and useful objects, as will appear, the invention consists in the novel features of the construction, combination and arrangement of the several parts to be described hereinafter, and illustrated in the accompanying drawings, in which:

Figure 1 is a side view of a clamp embodying the principles of my invention and shown as secured to an insulator support and in clamping engagement with a trolley wire.

Fig. 2 is an end view of Fig. 1.

Fig. 3 is a longitudinal sectional view of the clamp taken on the line 3—3 of Fig. 2.

Fig. 4 is a transverse sectional view of the clamp taken on the line 4—4 of Fig. 1; the

insulated support, in this view, being shown partly in section.

Fig. 5 is a view similar to Fig. 4, showing the clamp partly in section and the clamping members in open position.

Fig. 6 is a top view of the adjusting collar and showing the socket arranged therein.

The same reference characters indicate the same parts throughout the various views.

Referring to the drawings, I have illustrated my improved clamp as secured to a well known insulated hanger or support generally indicated at 1, and which, as shown, may be provided with suitable means, such as arms 2, Fig. 2, or a threaded boss 3, Fig. 4, for suspending or rigidly securing the hanger in position in the usual manner. Embedded within the insulation material 4 is a bolt 5, having its lower end projecting below the end of the hanger and provided with screw threads 6, for attachment to a clamp.

The clamp illustrated and described is particularly designed to clamp and hold a grooved trolley wire 10. It will be understood, however, that the invention is applicable for suspending trolley wires having other cross sectional shapes, and for supporting other wires and cables.

The clamp comprises, as shown, a pair of interchangeable clamping jaws 11, pivotally connected together by a hinge pin 12 passing through suitably apertured lugs 13. The lower ends 14 of the clamping jaws are for engagement with a trolley wire 10 or the like, and may be formed as shown or otherwise. Movable mounted between the jaws for rotary and vertical movement and extending through and beyond the upper ends thereof is a threaded socket 15, the lower end of which is provided with a head 16, adapted to receive and support a pair of angularly disposed and adjustable actuating members 17, which have their lower ends in abutting engagement as shown at 18. The opposite ends of the members 17, which constitute substantially a toggle and which will hereinafter be referred to as such, have engagement with and operate against the clamping jaws at 19. The upper end of the socket is formed with a polygonal flange 20, slidably receivable within the similarly formed opening 21, of the adjusting collar 22, which is disposed on top of the clamping

100

105

jaws and adapted to be clamped between the end surfaces of the jaws and the lower surface 23 of the support when the device is secured in position in a manner well understood in the art.

In practice when it is desired to suspend a trolley wire or the like the operation consists in first partially securing the invention to the threaded end 6 of an ordinary insulator or support by rotating the adjusting collar 22 in one direction. In this position of the device, as shown in Fig. 5, sufficient movement of the jaws 11 may be had to insert the trolley wire 10 between the clamping edges of the jaws. Upon rotation of the adjusting collar 22, and with it the socket 15, the upper end of the adjusting collar is brought into engagement with the surface 23 of the insulator and the socket drawn upwardly through the adjusting collar while the jaws 11 are prevented from rising by reason of their engagement with the lower end of the adjusting collar. The socket 15 in moving upward relatively to the jaws transmits movement to the toggle or angularly disposed actuating members 17 separating their ends which engage the jaws and thereby cause the clamping edges of the jaws to move into engagement with the wire.

Having fully described my invention and illustrated one embodiment of the same, I do not wish to be limited to the details of the construction shown since these can be changed without departing from the spirit of this invention.

I claim as my invention:

1. A clamp of the character described comprising clamping jaws to engage a wire, a rotatable member projecting between said jaws for attachment to a support, and a pair of pivotally mounted means interposed between the member and jaws and engaging both and operating by vertical movement of the member relatively to the jaws to actuate the jaws.

2. A clamp of the character described embodying clamping jaws for attachment to a wire, a rotatable member projecting between the jaws and movable vertically relatively thereto for attachment to a support, and means pivotally engaging said member and connecting said member and jaws and operating by vertical movement of the member to exert pressure against the jaws whereby the clamping edges of the latter will be caused to move toward each other.

3. A clamp of the character described embodying clamping jaws to engage and hold a wire, a rotatable member projecting between the jaws for attachment to a support, a pair of pivotally mounted means connecting the member and jaws and bearing against the interior surfaces of the jaws and operating by vertical movement of the member to impart clamping action to the

jaws, and means mounted on the clamping jaws and slidably secured to the rotatable member for actuating the latter.

4. A clamp of the character described embodying two clamping jaws, a rotatable member mounted between the jaws for vertical movement relatively thereto and provided with a screw thread for attachment to a support, a toggle supported by the rotatable member and engaging opposing inner surfaces of the clamping jaws, said toggle operating by vertical movement of the rotatable member and imparting clamping action to the jaws, and means for actuating the rotatable member. 80

5. A clamp of the character described embodying two clamping jaws to engage and hold a wire, a rotatable member provided with a shoulder mounted between the jaws for vertical movement relatively thereto, a toggle having engagement with the shoulder and with opposing inner surfaces of the jaws and coacting with the rotatable member to impart clamping action to the jaws, and an adjusting collar engaging the jaws and interlocked with the rotatable member against relative rotation but movable vertically relatively thereto for actuating said rotatable member. 85

6. A clamp of the character described embodying two clamping jaws adjustably connected together, a rotatable member arranged between the jaws for vertical movement relatively thereto and provided with a threaded socket and a head, a toggle mounted on said head and having engagement with inner opposing surfaces of the jaws whereby vertical movement of the rotatable member imparts clamping action to the jaws, and an adjusting collar engaging the jaws and actuating the rotary member and adapted to be clamped between a surface of a support and the end surfaces of the jaws when the clamp is installed. 95 100

7. A wire clamp comprising two clamping jaws connected together intermediate their ends, a toggle engaging inner opposing surfaces at the upper ends of the jaws and operating to force said ends of the jaws apart thereby to impart clamping action on the opposite ends of the jaws and means rotatable relatively to the toggle and jaws for simultaneously actuating the toggle and engaging a support. 115

8. A trolley wire clamp comprising a pair of adjustably mounted jaws connected together intermediate their ends, a rotatable supporting member, and a pair of angularly and adjustably disposed members interposed between the jaws and the supporting member adapted to increase the distance between the edges thereof, and engage the clamp when actuated by movement of the supporting member and thereby force the jaws into clamping position. 120 125 130

9. A trolley wire clamp comprising a pair of jaws adjustably connected together intermediate their ends, angularly and adjustably disposed means positioned between the 5 jaws and engaging the inner surface of the jaws, means engaging and supporting the angularly disposed means, means on the engaging means to secure the device to a support, the engaging means adapted to move 10 relatively to the jaws and change the angular relation of the angularly disposed and adjustable means and thereby change the angular relation of the jaw members relative to each other.
- 15 10. A trolley wire clamp consisting of a pair of adjustable jaw members having clamping edges at one end, toggle members positioned between the jaw members and engaging the jaw members, means holding 20 the jaw members in adjustable position relatively to each other and positioned between the clamping edges and the toggle member, and rotatable means for securing the clamp
- to a hanger and having means for simultaneously operating the toggle members to 25 force the jaws into clamping position.
11. A trolley clamp provided with adjustably mounted jaws, toggle members engaging the jaws and adapted to force them into clamping position, and means rotatively 30 mounted with respect to the jaws and toggle members and engaging the toggle members and adapted to cause them to approach a straight line and force the jaws into clamping position.
- 35
12. A trolley clamp provided with adjustably mounted jaws, toggle members between the jaws and engaging the inner surface of the jaws and rotatable means arranged between and adapted to engage the 40 toggle members and cause them to straighten out, thereby forcing the jaws into clamping position.

In testimony whereof I affix my signature.

SAMUEL S. MATTHES.
